UNITED STATES PATENT OFFICE

WILLIAM F. ANDREWS, OF BROOKLYN, NEW YORK, ASSIGNOR TO BAYLEY & SONS, INC.,
A CORPORATION OF NEW YORK

DESIGN FOR A LIGHTING FIXTURE

Application filed May 28, 1932. Serial No. 43,928. Term of patent 3½ years.

To all whom it may concern:

Be it known that I, WILLIAM F. ANDREWS, a citizen of the United States of America, and a resident of Brooklyn, in the county of Kings and State of New York, have invented a new, original, and ornamental Design for Lighting Fixtures of which the following is a specification, reference being had to the accompanying drawing forming a part there-

of. In the drawing the single figure is a perspective view of the lighting fixture wherein an opaque reflector A carries a translucent light diffusing disc B which in turn supports a central opaque hemispherical element C.

I claim:

The ornamental design for a lighting fixture as shown and described.

WILLIAM F. ANDREWS.
